UNITED STATES PATENT OFFICE.

ROY RODNEY WILEY, OF ST. CATHARINES, CANADA.

TRANSFORMER.

SPECIFICATION forming part of Letters Patent No. 738,864, dated September 15, 1903.

Application filed January 24, 1903. Serial No. 140,356. (No model.)

To all whom it may concern:

Be it known that I, ROY RODNEY WILEY, a citizen of the United States, residing at St. Catharines, in the county of Lincoln and Province of Ontario, Canada, have invented certain new and useful Improvements in Transformers, (Case 1,) of which the following is a full, clear, concise, and exact description, reference being had to the accompanying drawings, forming a part of this specification.

My invention relates to transformers or converters such as are commonly used for inductively transforming intermittent or alternating currents in one electrical circuit to intermittent or alternating currents in another electrical circuit, usually with a change of current and pressure. Such transformers as now built are usually provided with a core built of insulated soft-iron laminæ, upon which core are wound one or more primary coils and one or more secondary coils. The number of turns of wire in the primary and secondary coils is usually made different in order to get a ratio of transformation which is not unity. Such a transformer when placed in continuous service for the purpose of inductively transferring alternating currents from one circuit to another is subject to an increase in temperature. Part of this heating of the transformer is due to the resistance of the transformer-conductors to the flow of current therethrough. On account of the decreased cost of construction it is desirable that the conductors forming the transformer-coils be made of the smallest possible size; but opposed to this advantage gained in decreased cost is the disadvantage of a correspondingly-increased resistance and correspondingly-increased heating effect.

The heating of transformers has given rise to serious difficulty and inconvenience in the operation thereof due to the deterioration and breaking down of the necessary insulation when subjected to a high temperature.

The materials which may profitably be employed for insulating purposes will not withstand more than a certain maximum degree of temperature without such consequent deterioration. There is, however, marked economy resulting in the operation of transform-

ers at or only slightly below this maximum safe temperature, and a further economy and improvement would reside in the provision of means whereby every part of every coil might be operated at or slightly below this maximum safe temperature. In other words, it is desirable that the temperature be substantially the same throughout the transformer.

In order to prevent too great a rise in the temperature of commercial transformers, special provision has been made to insure the proper cooling thereof. In some cases the radiation of heat from the transformer to the surrounding air has been relied upon to cool the coils. In other instances the transformer proper, as above described, has been immersed in a receptacle filled or partially filled with oil. The circulation of this oil around the transformer parts has been relied upon to convey heat from the coils to the transformer case or receptacle through which it has been conducted to the outside air. It will be apparent that with such methods of cooling an increased area of contact between the heated parts of the transformer and the cooling medium will cause a corresponding increase in the cooling effect and a consequent decrease in the transformer temperature.

In transformers of the prior art it may be stated that in general an increase in the area directly affected by the cooling medium tends to require a corresponding increase in the length of the magnetic circuit. Such an increase in the length of the magnetic circuit, on the other hand, tends to cause an inefficiency of the transformer and to increase its size and cost.

In order to maintain a substantially uniform temperature throughout the transformer-coils, it is desirable that the inner conductors and parts be cooled to the same extent as the outer parts.

It is the object of my invention to provide a commercial transformer having a short magnetic circuit and at the same time a large total cooling area. It is further the object of my invention to provide a transformer having a substantially equal cooling area for each transformer-coil, whereby all the coils and all the conductors in each coil may operate at

substantially the same economical temperature, thus permitting the use of conductors of higher resistance than has heretofore been possible.

5 The construction of my improved transformer is such that only a small difference of potential exists between adjacent windings. In general I have provided a transformer of increased mechanical and electrical efficiency and of decreased cost of construction and operation.

I may attain the objects of my invention, preferably, by the provision of a laminated-iron core of substantially rectangular cross-section having a suitable rectangular opening in the middle. A core is thus provided having legs forming the four sides of an open rectangle. The conductors forming the transformer-windings are placed about the legs of this soft-iron core.

I find it desirable to make the windings in the form of so-called "pancake-coils," each pancake-coil being separately wound and insulated before assembly with the other transformer parts. A number of these pancake-windings are preferably placed side by side on a single leg of the transformer-core. It is desirable that the coils placed on the core substantially fill the opening within the core, and within this opening the coils or the insulating materials covering the coils are in contact one with another. On the outside of the core the coils are spaced apart, thereby leaving an open space between three sides of adjacent coils. These open spaces permit the free access and circulation of the cooling medium, whereby a large area and an equal area of each coil is directly exposed to the cooling effect of the cooling medium.

40 In order that the transformer-coils may be well insulated and cheaply formed, I wind the conductors or turns forming any one coil each in a plane parallel with the planes through all the other conductors or turns forming the same coil. Such a coil may be described as a "uniplanar-coil," in contradistinction to what may be termed "warped" coils, in which a complete turn cannot be made to lie in a single mathematical plane.

50 In addition to the equal and uniform cooling of the coils resulting from the above-described arrangement I find that by winding the primary and secondary coils each in such a pancake-coil the difference in electrical potential between adjacent turns may be very greatly reduced, thereby correspondingly reducing the liability of disruption of the insulation between adjacent turns.

I can more clearly describe my invention by reference to the accompanying drawings, in which—

55 Figure 1 is a perspective view of a transformer embodying my invention. Fig. 2 is a plan view thereof, the coils on one of the legs being shown in cross-section.

I have shown a laminated-iron core 3, built up of layers of soft sheet iron or steel in the manner well known to those skilled in the art. On two opposite legs of the rectangular core thus formed I place the primary coils 4 70 4, which in this instance are shown of comparatively fine wire, and the secondary coils 5 5, which are of fewer turns and correspondingly coarser wire. As well understood by those skilled in the art, the primary coils 4 75 5 may be connected in series or in series parallel with supply-mains leading from a suitable source of alternating current. The rectangular core 3 provides a single closed magnetic circuit for the lines of magnetic force 80 set up by the current flowing in the coils 4. In the present embodiment of my invention three such primary coils are shown on each leg of the transformer, the intermediate spaces being partially occupied by two secondary 85 coils. All of the coils are of the so-called "pancake" type, each being preferably wound upon a suitable form before assembly with the transformer core. As will be apparent from the drawings, the coils are comparatively 90 short along their magnetic axes as compared with their thickness perpendicularly thereto. There is practically the same difference of potential between the ends of each turn of such a coil. It will be seen that in such a 95 pancake-coil only comparatively few complete turns at any place are serially included in circuit between adjacent conductors, whereby the difference in potential between such adjacent conductors is not great enough to 100 readily break down the proper insulation thereof. I preferably employ such uniplanar-coils as heretofore described, the coils practically filling the opening in the core, within which opening the coils are brought into contact one with another. At the outer sides of the transformer, however, these uniplanar pancake-coils are spaced apart, in the manner best illustrated in Fig. 2, leaving openings between three sides of the adjacent rectangular coils. Thus the cooling medium employed, whether it be air or oil, within a transformer-case has free and direct access to three faces of each of three sides of each coil. The fact that the coils are each wound 110 with a comparatively small number of turns provides that no conductor is greatly removed from the surface of the coil, whereby the heat generated in an internal conductor is rapidly conveyed to the surface of the coil. It will 115 be seen, furthermore, that in accordance with my invention all of the coils, both primary and secondary, are substantially equally exposed to the cooling effect of the cooling medium, the areas of the surfaces of all the coils 120 in direct contact with the cooling medium being equal.

125 There is a considerable advantage gained by the number and relative displacement of the primary and secondary coils, as shown in 130

the accompanying drawings. As previously stated, the primary coils may be connected either in series or in series parallel with transmission-mains in the manner familiar to those skilled in the art, while the four secondary coils may be connected in series to give a certain maximum pressure, in series parallel to give one-half the maximum pressure, or in parallel to give one-quarter the maximum pressure. Since each of the secondary coils is symmetrically placed with regard to the magnetic circuit and the primary inducing coils, it will be apparent that under all arrangements of the circuit connections the magnetic induction and leakage will be perfectly balanced.

While I have herein shown and described one particular embodiment of my invention, it will be apparent to those skilled in the art that many modifications and changes might profitably be employed without departing from the spirit thereof, and I do not wish to be limited to the precise disclosure herein set forth; but,

Having described my invention, I claim as new and desire to secure by Letters Patent—

1. In a transformer, the combination with a hollow rectangular iron core, of a plurality of uniplanar, primary and secondary coils on a leg of said core, adjacent coils being in contact with one another on one side of said leg and having an intervening space on another side of said leg, substantially as described.

2. In a transformer, the combination with a hollow rectangular iron core providing a single magnetic circuit, of a plurality of uniplanar, primary and secondary coils on a leg of said core, adjacent coils being in contact with one another on one side of said leg and having an intervening space on another side of said leg, substantially as described.

3. In a transformer, the combination with a hollow rectangular iron core providing a single magnetic circuit, of a plurality of sandwiched uniplanar, primary and secondary coils on a leg of said core, adjacent coils being in contact with one another on the inside of said leg, and having an intervening space on the outside of said leg, substantially as described.

4. In a transformer, the combination with a hollow rectangular iron core providing a single closed magnetic circuit, of a plurality of sandwiched uniplanar, primary and secondary coils on opposite legs of said core, adjacent coils being in contact with one another on one side of said leg, and having an intervening space on another side of said leg substantially as described.

5. In a transformer, the combination with a hollow rectangular iron core providing a single magnetic circuit, of a plurality of sandwiched uniplanar, primary and secondary coils on opposite legs of said core, adjacent coils being in contact with one another on

the insides of said legs and having an intervening space on the outsides of said legs, substantially as described.

6. In a transformer, the combination with a hollow rectangular iron core providing a single magnetic circuit, of a plurality of sandwiched, pancake primary and secondary coils on a leg of said core, adjacent coils being in contact with one another on one side of said leg and having an intervening space on another side of said leg, substantially as described. 75

7. In a transformer, the combination with a hollow rectangular iron core providing a single closed magnetic circuit, of a plurality of sandwiched primary and secondary coils on opposite legs of said core, adjacent coils being in contact with one another on the insides of said legs and having an intervening space on the outsides of said legs, substantially as described. 85

8. In a transformer, the combination with a hollow rectangular iron core providing a single magnetic circuit, of a number of uniplanar pancake primary coils on each of two opposite legs of said core and uniplanar pancake secondary coils on said legs interposed between said primary coils, adjacent coils being in contact with one another on the inner sides of said legs and having an intervening space on the outer sides of said legs, substantially as described. 90

9. In a transformer, the combination with a hollow rectangular iron core, of a plurality of uniplanar, primary and secondary coils on a leg of said core, there being a greater space between adjacent coils at one side of said leg than at the other side of said leg. 100

10. In a transformer, the combination with a hollow rectangular iron core providing a single magnetic circuit, of a plurality of uniplanar primary and secondary coils, on a leg of said core, there being a greater space between adjacent coils at one side of said leg than at another side of said leg. 105

11. In a transformer, the combination with a hollow rectangular iron core providing a single magnetic circuit, of a plurality of sandwiched primary and secondary coils on opposite legs of said core, there being a greater space between adjacent coils at the outsides of said legs than at the insides of said legs. 115

12. In a transformer, the combination with a hollow rectangular iron core, providing a single magnetic circuit of more than two primary and secondary coils on each of two opposite legs of said core, said coils being in contact one with another at one side of each of said legs and having substantially equal areas exposed to a cooling medium. 120

13. In a transformer, the combination with a hollow rectangular iron core providing a single magnetic circuit of more than two primary and secondary coils on a leg of said core, said coils being in contact one with another at one

side of said leg, and having substantially equal areas exposed to a cooling medium.

14. In a transformer, the combination with a hollow rectangular iron core providing a single closed magnetic circuit, of a number of uniplanar pancake primary coils on each of two opposite legs of said core, and uniplanar pancake secondary coils on said legs interposed between said primary coils, there be-

ing a greater space between adjacent coils at the outsides of said legs than at the insides of said legs.

In witness whereof I hereunto subscribe my name this 17th day of January, A. D. 1903.

ROY RODNEY WILEY.
